UNITED STATES PATENT OFFICE.

WILLIAM D. FRICKS AND HARRY M. ASHE, OF ATLANTA, GEORGIA, ASSIGNEES, BY
MESNE ASSIGNMENTS, TO UNDERWOOD TYPEWRITER CO., OF NEW YORK, N. Y.,
A CORPORATION OF DELAWARE.

TYPE-WRITING MACHINE.

1,120,611.

Specification of Letters Patent.

Patented Dec. 8, 1914.

Application filed October 24, 1907. Serial No. 398,949.

To all whom it may concern:

Be it known that we, WILLIAM D. FRICKS and HARRY M. ASHE, citizens of the United States, residing at Atlanta, Fulton county, 5 State of Georgia, have invented certain new and useful Improvements in Type-Writing Machines, of which the following is a specification.

An object of the present invention is to 10 provide means for obtaining on a single sheet or strip of paper, a copy of a part of each of the entries made on separate sheets of paper which are successively inserted in and removed from the machine. For instance, it is customary in certain systems of 15 bookkeeping to enter upon the bills of customers from day to day the items chargeable against them, instead of entering these items in a ledger and then preparing the bills 20 from the ledger. In carrying out this system with our improved typewriter, the original bill, which goes to the customer, and a copy, are placed in the machine with a carbon sheet between, as is usual in making carbon duplicates. In addition we provide a third strip of paper, which is preferably 25 in the form of a ribbon, and upon which the amounts of the items charged to the several customers are entered in a column. By summing up this column at the 30 end of the day, the total of all charges for the day is obtained. The strip upon which the totals are made, which may be termed a "tally" sheet, is preferably provided with 35 a writing surface on one side and a carbon surface on the other, so that while the impressions are being produced by the typewriter ribbon on the front of the tally sheet, the carbon impressions are produced on the 40 original and duplicate bills between the tally sheet and the platen. We provide means whereby the tally sheet remains stationary 45 while the bills are being inserted in and removed from the machine and also convenient means for moving the tally sheet step by step as may be necessary to insert the several items. The receiving and supply spools for the tally strip may be journaled 50 in a bracket mounted on the right hand end of the carriage: said spools being above the platen so that the tally strip may extend downwardly from the supply spools around the platen outside of the usual work sheets.

and upward to the receiving spool. A 55 presser finger carries a pressure roll to bear against the tally strip and hold it in driving relation to the platen, and also carries a guide through which the tally strip extends; 60 said presser finger being spring pressed against the platen but movable therefrom to lift the pressure roll and also positively move the tally strip away from the platen, thereby permitting the platen to be rotated and feed the work sheets independently of the tally strip. Said guide also serves as a 65 tearing edge for the tally strip. The guide finger may be lifted and held from the platen by suitable means, such as a finger actuated cam.

Other features and advantages will here- 70 inafter appear.

The invention will be described more particularly in connection with the accompanying drawings, in which,

Figure 1 is a front view of a typewriter 75 carriage having our invention applied thereto; Fig. 2 is an end view of the same partly in section on the line 2—2 of Fig. 1; Fig. 3 is a view similar to part of Fig. 2 but showing the mechanism in a different position; Fig. 4 is a detail plan view of a presser finger and paper guide.

Our invention can be applied to any type-writing machine, but it is particularly applicable to machines having undivided or 85 unipartite cylindrical platens and especially to front strike machines, and we have illustrated it in connection with a machine of the latter class.

Referring to the drawings, 1 indicates the 90 carriage of a typewriting machine and 2 the platen, which is mounted in suitable bearings in the carriage. A bar 3 extends along the carriage in front of and below the platen and on this bar is mounted a paper finger 4, 95 which is constantly pressed toward the platen by a spring 4^a. Beneath the platen are the paper feed rolls 2^a, 2^b. These rolls are of ordinary construction and are yieldingly pressed against the platen in the usual 100 manner by suitable springs. In the present instance the paper feed rolls only co-operate with the portion of the platen to the left of the tally strip, the rolls which in ordinary typewriting machines would bear on 10 the tally strip being omitted. This permits

of feeding the bill blanks or other sheets of paper in the machine without moving the tally strip when the presser finger is raised. With the exception of the omission of certain of the feed rolls, the paper feeding devices shown in the drawing are those of the well known L. C. Smith & Bros. typewriting machine, although any other suitable paper feeding mechanism may be used in connection with our improvements.

At the right end of the carriage we provide a special presser finger or device 5 which is hinged to a suitably fixed support 6. As shown, this support is carried by the bar 3, but it will be obvious that it may otherwise be secured to the carriage. The presser finger 5 is connected to its support by a hinge joint 7 and is normally pressed against the platen by a spring 8. This finger is offset toward the center of the platen above the printing plane and in its offset portions are preferably mounted one or more anti-friction rolls 9, adapted to reduce the friction between the finger and the platen or paper. At the upper end of the presser finger, and connected with the offset portion, is a paper guide 10 toward the center of the platen and likewise above the printing plane; this guide is preferably in the form of a flat loop adapted to receive and guide a paper ribbon 11, and having a straight upper edge 10^a which forms a paper cutter by means of which the tally strip may be conveniently torn off when it is desired to remove a portion of it.

We provide means for moving the presser finger to and from the platen and for holding it away from the platen when desired. As shown these means comprise a thumb or cam lever 12 pivotally connected to a lug 13 at the right side of the presser finger. When this thumb lever is turned out into the position shown in Fig. 2, the spring 8 is permitted to hold the presser finger yieldingly against the platen, or against the paper running over the platen, and when the thumb lever is thrown into the position shown in Fig. 3, the presser finger is held away from the platen. While in this position the thumb lever 12 may rest directly on the platen surface, but we prefer to provide a fixed part 14 against which the thumb lever may bear.

The tally sheet 11 is preferably a strip or ribbon of paper having a writing surface on its outer side and having its inner surface covered with a carbon preparation. It will be evident however that instead of coating the surface of the tally strip with carbon a thin strip of carbon may be arranged within the tally strip and made to travel with it.

Upon the rear of the carriage is a support carrying two spools 16, 17, the former spool carrying the supply roll of the tally strip and the latter spool being adapted to receive the tally strip as it leaves the platen.

These spools may be of any ordinary construction. For convenience they are removably held upon their spindles by the thumb nuts 18. At the right end of each spool is a pulley and a band or belt 19 effects a friction drive between these pulleys so that when the delivery spool 16 is turned the receiving spool 17 will be turned simultaneously. The spool 16 is turned automatically by the feeding of the tally strip to the platen and as the diameter of the roll on the supply spool 16 is usually much greater than the diameter of the roll on the winding spool 17, the diameter of the pulley on the latter spool is smaller than the diameter of the other pulley, so that the peripheral speed of the roll on the spool 17 is always as great as that of the roll on spool 16 and slack in the tally strip is thereby prevented. Undue tension on the tally strip is prevented by slippage of the band 19 on its pulleys.

The platen may be rotated either by means of the band wheels 21 secured to the ends of the platen axle, or by the usual line-space mechanism comprising the line-space ratchet wheel 22.

The operation of the invention when used in preparing bills is as follows: The end of the tally strip is carried from the spool 16 over the paper table 20, around the platen, 95 through the guide 10, and connected with the core of the spool 17. When it is desired to insert a bill the presser finger is held away from the platen, as shown in Fig. 3. A bill A, together with a carbon C and a 100 duplicate bill B may then be inserted in the machine without disturbing the tally strip, the right ends containing the figure columns of the bill and duplicate being within the tally strip, as shown in Fig. 1. During the 105 adjustment of the bill and duplicate the tally strip will not be disturbed if the presser finger be maintained away from the platen, as illustrated in Fig. 3. When the papers have been properly adjusted for writing, the finger lever 12 is thrown out and the presser finger permitted to spring against the platen, as shown in Fig. 2. The typewriter is then operated in the ordinary way and two copies of the items on the bill, together with three copies of the figures are produced. If more than one item is written the tally sheet will be fed forward with the bill in duplicate on turning the platen. After the last item has been entered on the 120 bill the platen is turned one line space to leave the tally sheet in the proper position to receive the first figure of the next bill and then the presser finger is thrown back and the bill and duplicate removed without disturbing the tally sheet.

It will be evident that different results may be produced with our invention by different manipulations of the machine. Thus in preparing bills from a ledger the totals 130

are ordinarily carried out to the right and by arranging the bills in the typewriter so that the total columns are under the tally sheet and the item columns exposed only 5 the totals will be printed on the tally sheet and these totals may be printed as closely together as desired. When the system of bookkeeping in use requires daily entry of 10 items on bills, the bills are successively placed in the typewriter and the amount of each item is written on the tally sheet. By adding up the items of the tally sheet at the end of each day the total of charges for the 15 day can be obtained. In totaling the bills at the end of the month the totals may be produced on the tally sheet and added and a check on the daily entries thus obtained.

It will be evident that various changes in 20 details of construction and arrangement may be made without departing from the spirit and scope of our invention.

Without limiting ourselves to the precise form of the invention illustrated and described, we claim,

25 1. The combination with a platen for supporting a work-sheet, of a device for guiding a tally-sheet in overlapping relation with respect to said work-sheet, mechanism for rotating said platen to concomitantly feed said work-sheet and said tally-sheet, and means for moving said device and with it the tally-sheet away from the platen to free said tally-sheet from actuation by the platen while said work-sheet remains under 35 the control of said line-spacing mechanism to be fed thereby independently of said tally-sheet.

2. In a typewriting machine, the combination with the usual carriage, platen and 40 paper feeding devices, of a presser finger at the right end of the carriage, means for yieldingly holding said finger against the platen, means for holding the finger away from the platen, and means on said finger 45 for guiding a tally strip.

3. The combination with a platen arranged to receive a work-sheet and support the same, means for maintaining a combined carbon sheet and recording tally-sheet in 50 superposed relation with respect to said work-sheet in such position that matter written on said tally-sheet can be transferred from the tally-sheet to said work-sheet by the carbon portion of said tally-sheet, and means to carry the tally-sheet against and away from said platen to cause 55 said sheets to be fed together or to permit the work-sheet to be fed independently of the tally-sheet.

60 4. In a typewriting machine, the combination with a carriage, a single platen thereon, and paper feed rollers coöoperating with the platen, of tally strip spools, a support for said spools carried by the carriage, a 65 presser finger upon the carriage and adapted

to bear on a tally strip carried by said spools, means for holding said finger yieldingly upon said strip and platen, and means to move and hold said finger away from the platen independently of the paper feed 70 rollers, and thereby permit the platen to be rotated and feed a work-sheet thereon independently of the tally strip.

5. The combination with a platen, of means for supporting a work-sheet and a 75 tally-sheet in over-lapping relation so that an ordinary impression can be made on the one and a carbon of the same subject matter on the other, and pivotal means for positively moving said tally-sheet away from 80 said work-sheet to permit an independent relative movement between said work-sheet and said tally-sheet.

6. The combination with a platen arranged to support a work-sheet, of means for pressing a tally-sheet on said platen at a certain point so as to cause the tally-sheet to be fed concomitantly with said work-sheet by a movement of said platen, and means for moving said tally-sheet away from the 90 platen at said point to enable an independent movement of said work-sheet with said platen.

7. The combination with a single platen arranged to receive a work-sheet, of means 95 for supporting a tally-sheet in overlapping relation with respect to said work-sheet, pressure means for causing said work-sheet and said tally-sheet to bear with pressure on said platen so as to be fed at the rotation of 100 said platen, and means to relieve the pressure of the tally-sheet on the platen while the pressure of said work-sheet is retained.

8. In a typewriting machine, the combination with a carriage, a single platen, and 105 paper feeding devices coöoperating with said platen, of a support mounted on the carriage at the right end thereof, a pair of spools on said support, a presser finger arranged to coöperate with the right end of 110 the platen to hold a tally strip supported by said spools against the platen, whereby the strip will be fed when the platen is rotated, and means for moving and holding the presser finger away from the platen 115 independent of movement of any other paper-feeding devices, and thereby releasing the tally-strip from the platen.

9. In a typewriting machine, the combination with the carriage, a platen, and the 120 usual paper feeding devices, of a support mounted on the carriage at the right end thereof, a pair of spools on said support, a presser finger arranged to coöperate with the right end of the platen to hold a tally strip supported by 125 said spools against the platen, whereby the strip will be fed when the platen is rotated, and means for holding the presser finger away from the platen to permit the latter to be rotated without 130

moving the tally strip, said means comprising a thumb lever mounted on the presser finger.

10. In a typewriting machine, the combination with the carriage and the platen supported thereon, of means for supporting a tally strip in operative position relatively to said platen, a presser finger pivotally mounted on the carriage, and a guide for the 10 tally strip carried by said presser finger.

11. In a typewriting machine, the combination with the carriage and the platen supported thereon, of means for supporting a tally strip in operative position relatively 15 to said platen, a presser finger pivotally mounted on the carriage, and a guide for the tally strip carried by said presser finger, said guide having an edge extending across the tally strip by means of which the latter 20 may be conveniently torn and removed.

12. In a typewriting machine, the combination with a carriage and a single platen, of a tally strip spool supported on the carriage, means for guiding a tally strip from 25 said spool around the platen, a presser finger adapted to bear on the platen and constituting with the platen the sole means for feeding the tally strip, and paper feed devices 30 cooperating with portions of the platen not affected by the presser finger, whereby a paper surrounding the platen within the tally strip may be fed independently of the tally strip.

13. The combination with a platen arranged to support a work-sheet, of means 35 for supporting a tally-sheet in superposed relation with respect to said work-sheet on said platen, means for causing pressure of said tally-sheet on said platen so as to enable said platen to feed said tally-sheet with said work-sheet during a rotation of said platen, and means for positively moving said tally-sheet away from said platen and said work-sheet to enable said work-sheet to 40 be fed with said platen while said tally-sheet remains stationary.

14. A typewriting machine combining a 45 rotary platen, means for supporting on said platen a work-sheet and a tally strip superposed on said sheet, means for advancing the work-sheet around the platen independently

of the strip, receiving and supply spools for said strip, a support in which said spools are journaled and maintaining a fixed relation to the axes of said spools, and a frictional 55 driving connection between the spools tending to rotate the receiving spool at a greater angular speed than the supply spool.

15. A typewriting machine combining a revoluble platen, a delivery spool from 60 which the tally strip is led around the platen, means to press the strip against the platen to receive the type impressions and to enable the platen to pull the strip off from the delivery spool, a device independent 65 of said means for feeding a work-sheet around said platen, a winding spool to which the written strip is delivered from the platen, and a friction-drive between the delivery spool and the winding spool to enable 70 the former to drive the latter.

16. A typewriting machine combining a carriage, a platen support thereon, means for supporting a sheet in operative relation to said platen, a presser device mounted on 75 the carriage and provided with an off-set portion extending toward the center of the platen and above the printing plane, and means mounted upon said portion extending between the sheet and platen and adapted 80 by the movement of the presser device to sheet-releasing position to carry the sheet away from the platen.

17. A typewriting machine combining a carriage, a platen support thereon, means 85 for supporting a sheet in operative relation to said platen, a presser device mounted on the carriage, and a guide mounted on said device and extending toward the center of the platen and between the sheet and platen, 90 and adapted to carry the sheet away from the platen when said device is moved to sheet-releasing position, said guide being provided with a sheet-cutting edge.

In testimony whereof we affix our signatures in presence of two witnesses.
